By his Atty
W. G. Grant & Co

United States Patent Office.

WILLIAM BLACK, OF HAGERSTOWN, INDIANA.

Letters Patent No. 99,283, dated February 1, 1870.

IMPROVEMENT IN SEWING-MACHINE

The Schedule referred to in these Letters Patent and making part of the same.

To all whom it may concern:

Be it known that I, WILLIAM BLACK, of Hagerstown, in the county of Wayne, and State of Indiana, have invented a new and improved Sewing-Machine; and I do hereby declare that the following is a full and exact description thereof, reference being had to the accompanying drawings, and to the letters of reference marked thereon, in which—

Figure 1 represents a side view of my sewing-machine.

Figure 2 represents an end view of the same.

Figure 3 represents a view of the under side of the machine.

Figure 4 represents the feeding-device detached from the machine.

Figure 5 represents the shuttle-carrier.

The object of my invention is to construct a sewing-machine, which will be easily managed, and simple in its parts, so that it will be inexpensive, and yet have all the advantages of high priced shuttle-machines, and it relates to the construction and arrangement of the mechanism by which I impart the proper movements to the shuttle-carrier, needle-arm, and feeding-dog.

To enable others skilled in the art to make and use my invention, I will proceed to describe the same, with reference to the drawings, in which—

A represents the bed-plate of the machine, to which is attached the standing frame B, which carries at its forward end the presser-foot C, while the needle-bar D is pivoted to its rear end at a.

To the under side of the bed-plate A is also attached the plate E, which serves as bearing and guide to the shuttle-carrier F, which is pivoted to it, and oscillates on its pivot b.

The shuttle-carrier F has a direct vibrating motion with the needle, by means of the connecting-rod f, which has one end attached at c, to the shuttle-carrier, and the other at d, to the needle-bar D.

Motion is imparted to the machine by means of the pulley G, which is hung in bearings ee, attached to the under side of the bed-plate A.

This pulley G rotates the axle g, to which is attached the disk-crank H. The object of this crank is two-fold.

First, it operates the needle-bar D, by means of the slotted connecting-rod h, which connects the two together; and

Second, by means of the swell or cam m thereon, it raises the feeding-hand I against the under side of the work, after the needle has ascended.

This hand is moved laterally to move the work for a new stitch, by the projection k on the side of the pulley G.

When the projection m has passed the feed-hand I, this latter falls back again on to the circular part of the cam, down clear of the work, while the needle is descending, and is immediately drawn back by the spring l, to feed for the next stitch.

The length of the stitch is regulated by the distance that the feed-hand is made to slide in its bearings by the cam K, which distance may be made to vary as follows:

A lever, k is pivoted to the under side of the cloth plate at n, and one end is free to come in contact with a pin or stud, r, on the feed-hand bar at any point in the length of its play in its bearings, fixed by the pin and holes, p q. Thus, the bar of the feed-hand or dog may slide the whole of the distance due to the spread of the cam K, or it may be arrested by the end of the lever, bearing against the pin r, so that but a portion of the cam-surface will act to throw it forward.

The operation of the machine is as follows:

The shuttle L being introduced into the recess provided for it in the upper part of the shuttle-carrier F, and the needle being fed from a spool placed on the spool-carrier S, through the tension-regulator t, and guides, the pulley G is revolved, and with it the crank H, which operates the needle-bar D, by means of the slotted rod h, the shuttle-carrier moving forward and backward by means of the connecting-rod f, attached to the lower end of the needle-bar D, at the same time that a proper feeding-motion is given to the feed-hand I, by the projection k on the pulley G, and cam projection m on the crank H, in connection with the spring l.

What I claim as my invention, and desire to secure by Letters Patent, is—

The described arrangement of mechanism for operating the needle-arm, and the shuttle-carrying lever, the same consisting in the slotted link h, connecting the crank H to the needle-arm, and the link f connecting the free end of the shuttle-carrier to the lower arms of the needle-bar.

Also, in connection with the above-named arrangement, the lifting-cam m on the crank, and the side cam k, on the driving-wheel or pulley, for imparting the positive movements to the feeding-dog.

In testimony that I claim the foregoing invention, I have hereunto set my hand, this 13th day of February, 1869.

WILLIAM BLACK.
